HEADSET OR THE LIKE

Eliot F. Noyes, New Canaan, Conn., assignor to International Business Machines Corporation, Armonk, N.Y., a corporation of New York

Continuation-in-part of design application Ser. No. 9,849, Dec. 19, 1967. This application Aug. 1, 1968, Ser. No. 12,984

Term of patent 14 years

Int. Cl. D14—01

U.S. Cl. D26—14

FIG. 1

FIG. 3

FIG. 2

FIG. 4

FIG. 5

FIG. 6

FIG. 1 is a front view of a headset or the like illustrating my new design;

FIG. 2 is a bottom perspective view thereof;

FIG. 3 is a right perspective view thereof;

FIG. 4 is a front view with the wands turned from the position shown in FIG. 1;

FIG. 5 is a rear view with the wands expanded for use; and

FIG. 6 is a top view thereof.

The dominant features of my design reside in the portions shown in full lines.

This is a continuation-in-part of design application Ser. No. D. 9,849, filed Dec. 19, 1967 and now abandoned.

I claim:

The ornamental design for a headset or the like, substantially as shown and described.
